UNITED STATES PATENT OFFICE.

HORACE HOLLY SMITH, OF TACOMA, WASHINGTON.

SEPARATOR.

1,308,920.

Specification of Letters Patent.

Patented July 8, 1919.

Application filed June 28, 1918. Serial No. 242,455.

To all whom it may concern:

Be it known that I, HORACE H. SMITH, a citizen of the United States, and a resident of Tacoma, in the county of Pierce and 5 State of Washington, have invented a new and Improved Separator, of which the following is a description.

My invention relates to a separating apparatus and although capable of separating 10 various materials is more particularly intended for use in the separation of ores and the like, especially the separation of slate from quartz or slate from diorite.

In general the apparatus is designed to 15 separate approximately round, triangular, or cubical particles from flat or elongated particles without reference to weight or other physical properties of the materials. As an example; slate fractures or breaks 20 under some forms of crushing into essentially flat or needle-like lumps which range from enormous size down to the smallest particles. On the other hand, quartz will break into approximately triangular or cubical pieces in almost all instances. In producing my invention recognition is taken 25 of the difference in fracture and the resulting shapes and I take advantage of the same to separate the quartz or other particles of 30 like shape and direct the same to a compartment or place of deposit, while the flat or elongated particles are separately deposited into any suitable receptacle or directed to 35 any desired point of delivery. Thus, the apparatus depends for its operation on the different ways in which mineral quartz, coal, 40 gravel, slate, diorite, or other rocks or minerals break into lumps, and the different exposed surfaces presented by the different shapes govern the separating action of the apparatus, it being understood that the invention is adapted for the separation of 45 seeds or other materials presenting the general difference in shapes referred to.

In carrying out my invention in practice 50 use is made of an endless belt presenting an incline for each separating unit and a transverse conveying roller, together with means to deliver the material at the angle of the incline and roller, the belt, specifically, presenting grooves and ripples and the conveyor roller presenting a spiral.

The invention will be particularly explained in the specific description following. 55 Reference is to be had to the accompanying drawings forming a part of this specifi-

cation, it being understood that the drawings are merely illustrative of one example of the invention.

Figure 1 is a side elevation of a separator 60 embodying my invention;

Fig. 2 is a plan view thereof;

Fig. 3 is a transverse vertical section on the line 3—3, Fig. 1;

Fig. 4 is an enlarged cross section of a 65 portion of the belt.

In carrying out my invention in accordance with the illustrated example an endless belt, 10, is employed which runs over end rollers 11, 11^a, mounted in any suitable 70 frame 12. The belt at the bottom or idle run extends beneath rollers 13 a short distance from the rollers 11, 11^a and between the rollers 13 the belt rests on idlers 13^a. The upper working run of the belts runs 75 about rollers 14 and in connection with the working face of the belt I employ transverse conveyer rollers, there being three in the illustrated example and designated 15, 15^a, 15^b. The rollers 14 are at elevations relatively to the conveyer rollers so that the belt will present an incline at each separating 80 unit, the inclines being designated 10^a, 10^b, 10^c and up which inclines relatively flat particles will travel. The belt 10 in the working 85 face thereof is corrugated or grooved, the grooves, 16, running with the direction of travel of the belt and in practice being parallel or substantially so with the side edges of the belt, the grooves thus producing intermediate ripples or ribs. As best seen in Figs. 90 3 and 4 the grooves 16 present angular walls with intermediate flat surfaces 19. Each groove presents a flat bottom 17 and flaring side walls 18. Advantageously and with 95 good results the side walls 18 are at an angle of inclination of twenty-five degrees (with reference to the belt surface). Also, as clearly seen in Figs. 3 and 4, the respective grooves or corrugations 16 are successively of decreasing depth from one side edge of the belt toward the opposite edge where they merge or substantially so into the belt surface. In practice the width of the surfaces 19 separating adjacent grooves 100 16 are equal to the width of flaring side walls 18. The same angle of the walls 18 and the relative width of the intermediate surfaces 19 are preserved though the depth of the grooves decreases. I would mention also 105 110 that the maximum depth of the grooves varies with the material being treated, a

lesser depth being required according to the smallness of the particles of the material being treated.

- 5 The conveyer rollers 15, etc., have suitable journals at the ends and between the journals each roller presents a conical core 20 and a spiral rib 21, so that the roller is in the form of a screw, the convolutions of the spiral lying within the same cylindrical surface. Thus, since the diameter of the conical core increases gradually from one end of the spiral toward the opposite end, the depth of the spiral groove formed by the rib 21 will be of decreasing depth from one end of the screw to the other, that is to say, from one side edge of the belt toward the opposite edge, the greater depth of the spiral being at that side of the belt having the deeper grooves. The spiral rib 21 has radial protuberances 22 that enter the grooves of the belt and act as agitators.

Three separating units are shown in the illustrated example and the material is fed to the first unit through a chute 23 or the like which delivers the material at the angle formed by the incline 10^a and the separating roller 15 and adjacent to one side of the belt, that is to say, the side having the deepest grooves. The angle of the belt at the inclines is varied by means of separating rollers at the under side of the belt, there being a single roller 26 at the first separating unit, two rollers 26^a at the second unit, and a single roller 26^b at the third unit. In the second unit, in which a relatively large amount of material drops a considerable height from the first unit, the two rollers and a relatively long belt-run are employed, whereby to effectively sustain the load dropped thereon and maintain the belt at the proper angle. Suitable means are provided to move the rollers 26, etc., against the belt or away from the same to vary the angle of the incline, there being shown for the purpose screws 27, 27^a, 27^b, serving to actuate the slidable bearings of the rollers.

The separating is done at the immediate angle formed by the spirals and the inclined belt surfaces. The angle of the belt relatively to the spiral having been adjusted so that the flat or like particles to be separated out will be caused to travel up the belt, because of their greater tendency to do so than the particles approximately round, cubical, or the like, the material is fed to the belt near one side edge by the chute 23. The size of the core 20 increases rapidly from the feed side of the belt and this increase forces the material traveling along the spiral farther and farther across and up the belt as the material approaches the end of the spiral. The increasing diameter of the core obviously causes the transversely moving material to move gradually higher on the belt, the idea being to give all the material

less and less of an angle to travel as separation progresses the distinction in shape of the particles becomes less and less owing to the flat or approximately flat particles having started up the incline; thereby minimizing the travel of the separated material carried by the belt. A less depth of the belt grooves suffices for the arrest of the pronouncedly flat particles and as those particles which are less flat are gradually eliminated at the deeper belt grooves, the general work thrown on the transverse screws in forcing the material across the deeper grooves and ribs is lessened by gradually reducing the depth of the belt grooves to that actually required to arrest the remaining flat particles. The screw carries across the belt the particles not taken up the incline and discharges at the opposite side from the point of feed. It is to be noted that on the upper or feed side of the spiral the latter and the belt are traveling away from one another; thus, none of the fed material gets between the spiral and the belt. The spiral serves to carry the material or the separated portion of it across the belt transversely to the direction of travel of the latter and at the same time it serves as a guard against any of the material passing off the end of the belt at the opposite side. The spiral rib of the conveyer screw is made with a wide face to withstand wear and make easy riding on the belt. As the material passes to the top of the first incline 10^a and about the first roller 14, the material falls toward the second incline; with the purpose of distributing the material and directing it laterally toward the feed side of the belt, I provide inclined baffles 24 which are formed on or secured to a backing board or plate 25 made rigid in any suitable manner with the adjacent portions of the frame 12. In handling certain material, more or less baffles 24 may be employed. If the product coming from the belt over the first roller 14 is sufficiently clean the chutes formed by the baffles will be arranged to deposit the material at the side of the belt to be taken away but if the material still needs cleaning the chutes again deposit the product on the belt at the second incline adjacent to the second screw 15^a. If further cleaning is required a second set of baffles or chutes 24^a is provided on a suitable support 25^a. It will be understood that any suitable means may be provided such as chutes or the like for the separated materials, these not being shown as they form no part of the invention. The driven roller 11^a may receive power from any suitable source, there being shown a pulley belt 28 on the shaft of said roller adapted to receive a drive belt (not shown). Also, the roller 11 is adapted to be shifted to constitute a belt tightener, there being indicated as one means for the purpose a screw 11^b.

In operation, material is fed through the chute 23 or the like at the angle of the first screw 15 and the belt, and adjacent to the deepest part of the spiral groove, so that the wider radius of the ribs serve as a guard to prevent the feed material from passing over the adjacent side of the belt. The greater depth of the belt grooves at that side of the belt at which the material is delivered, 10 serves to arrest those particles not pronouncedly flat and also the greater depth of the spiral ribs gives the screw a capacity to carry the relatively large amount of material across the belt. As the material is carried transversely of the belt, an increasing amount of the flat particles is carried up by the belt so that a less depth of spiral grooves in the screw and a less depth of belt grooves suffice to separate the remaining flat particles and carry the remaining particles over the belt to be discharged from the apparatus. All the material carried up by the belt of the first unit drops to the belt of the second unit, being carried over the first roller 20 25 and baffles 24 are employed according to the character of the material and the degree to which separation takes place in the first unit, in order to distribute the material over the belt of the second unit and more or less to that side of the belt at which the depth of the spiral screw is positioned. The same separating process takes place as in the first unit and if the separation of the comparatively flat particles is not completed, it will 30 35 be completed in the third unit or additional units as may be found necessary according to the character of the material being treated.

I would state in conclusion that while the illustrated example constitutes a practical embodiment of my invention, I do not limit myself strictly to the mechanical details herein illustrated, since manifestly the same can be considerably varied without departure 40 45 from the spirit of the invention as defined in the appended claims.

Having thus described my invention, I claim as new, and desire to secure by Letters Patent:

50 1. A separator of the class described including an endless belt, and a conveyer screw disposed transversely of the working face of the belt, said belt rising at an incline from the screw and presenting alternate grooves and ribs running in the direction of travel of the belt, and thereby crossed by the screw so that the transverse movement of relatively flat particles by the screw will be arrested by the belt grooves and ribs 55 60 to permit said particles to be carried up by the belt.

2. A separator of the class described including an endless belt presenting an incline and having in the working face thereof alternate grooves and ribs running with the

direction of travel of the belt, and a transverse separator screw, the convolutions of which lie in the same cylindrical surface.

3. A separator of the class described including an endless belt, and a feed screw 70 presenting a conical core and spiral rib the convolutions of which lie in the same cylindrical surface; together with means to deliver the material to be separated to said belt adjacent that end of the roller having the smaller end of the core so that the greater depth of the spiral ribs serves as a guard to prevent the material passing from the belt at the side adjacent to said deeper ribs.

4. A separator of the class described including an endless belt, a conveyer screw disposed transversely of the belt adjacent to the working surface thereof, said screw presenting a spiral groove of decreasing depth from one end of the screw to the other, and 80 85 said belt rising at an incline from the screw.

5. A separator of the class described including an endless belt having grooves in the working face thereof and running with the direction of travel of the belt, and a transverse conveyer screw adjacent to the working 90 95 face of the belt, the convolutions of said screw having agitating protuberances at the periphery adapted to enter the grooves of the belt.

6. A separator of the class described including an endless belt having grooves in the working face thereof and running with the direction of travel of the belt, and a transverse conveyer screw adjacent said 100 105 face, the depth of the grooves decreasing from one side of the belt to the other and toward the discharge end of the screw.

7. A separator of the class described including and endless belt, a transverse conveyer screw adjacent to the working face of the belt, said belt rising at an incline from the screw, a roller beneath the belt at the incline, and means to move the roller relatively to the belt to adjust the angle of inclination of the latter.

8. A separator of the class described including an endless belt presenting a transverse conveyer screw adjacent to the working face of the belt, said belt rising at an incline from the screw and having alternate grooves and ribs in the working face thereof, said grooves presenting flaring side walls at an angle of approximately twenty-five 110 115 degrees to the belt surface.

9. A separator of the class described including an endless belt presenting a transverse conveyer screw adjacent to the working face of the belt, said belt rising at an incline from the screw and having alternate 120 125 grooves and ribs in the working face thereof, said grooves presenting flaring side walls at an angle of approximately twenty-five degrees to the belt surface, the intervening ribs presenting flat surfaces approximately 130

the same width as the flaring walls of the grooves.

10. A separator of the class described including an endless belt, a transverse conveyer screw adjacent to the working face of the belt, and means to deliver material to the belt adjacent to one side edge thereof and thus adjacent to one end of said screw, said screw presenting a spiral groove decreasing in depth from the end adjacent to said feed means.

11. A separator of the class described including an endless belt, a plurality of transverse conveyer screws adjacent to the working face of the belt and discharging the material conveyed thereby from the separator, said belt presenting inclines rising from the respective screws, and presenting drops between the inclines so that material will feed by gravity from one incline of said belt to the next following incline thereof.

12. A separator of the class described including an endless belt, a plurality of transverse conveyer screws adjacent to the work-

ing face of the belt, said belt presenting inclines rising from the respective screws, and presenting drops between the inclines so that material will feed by gravity from one incline to the next following incline; together with baffle means between one incline and a following one and adapted to deflect laterally the material received thereby.

13. In a separator of the class described, a belt having grooves in the working face thereof and running in the direction of the travel of the belt, the depth of the grooves increasing from one side edge toward the opposite side edge of the belt, together with a transverse conveyer screw to move material across said belt.

14. In a separator of the class described, a belt having grooves in the working face thereof running in the direction of the travel of the belt, said grooves having flaring side walls at an angle of approximately twenty-five degrees with respect to the belt surface, together with a transverse conveyer screw to move material across said belt.

HORACE HOLLY SMITH.
